UNITED STATES PATENT OFFICE.

HENRY J. DAVIES, OF BROOKLYN, NEW YORK.

DESIGN FOR CLOCK-PENDULUM.

Specification forming part of Design No. 6,963, dated October 21, 1873; application filed June 16, 1873.
[Term of Patent 3½ years.]

To all whom it may concern:

Be it known that I, HENRY J. DAVIES, of Brooklyn, in the county of Kings and State of New York, have invented a Design for a Clock-Pendulum, of which the following is a specification:

The nature of my design is fully represented in the accompanying drawing, to which reference is made.

A A A are three cylinders, which are furnished with molded ornamental caps F F at both ends, and connected by cross-bars B B. On the middle of the bottom bar B there is a pointed ornament, C. From the upper bar B two parallel rods, R, extend upward to a cross-bar, D, which is connected with the pendulum-rod E. Three shorter rods, G G G, extend

from the cross-bar D to another bar, I, of the same form, which is arranged a short distance above the upper cross-bar B. These two bars D and I have on their ends pointed ornamental finials J J. A bar, K, crosses the short rods G G G about midway between the bars D and I. An ornamental piece, L, is arranged between the bar I and the upper bar B that connects the cylinder A.

What I claim as my invention is—

The design for a clock-pendulum, substantially as shown and described.

HENRY J. DAVIES.
